UNITED STATES PATENT OFFICE.

JEREMIAH CAMPBELL, OF PROVIDENCE, RHODE ISLAND.

COAL-HOISTING APPARATUS.

No. 832,867.

Specification of Letters Patent. Patented March 24, 1908.

Application filed February 13, 1907. Serial No. 357,127.

To all whom it may concern:

Be it known that I, JEREMIAH CAMPBELL, of Providence, in the county of Providence and State of Rhode Island, a citizen of the United States, have invented a new and useful Improvement in Coal-Hoisting Apparatus, of which the following is a specification.

My invention relates especially to an improved means for operating the jaws of the grab and for maintaining the operating rope upon the sheaves; the housings to the sheave being automatically kept in position to allow the rope to reeve through them without engagement with their edges. This is an important condition because of the great strain under which the rope operates in lifting the load which strain would otherwise tend to mar both the rope and the housing if they were allowed to rub past each other.

My invention relates also to an improved form of yielding stop member or cushion intended to reduce the jar made by the grab against the trolley or other fixture with which the grab ordinarily contacts when it has reached its uppermost position.

My invention will be understood by reference to the drawings in which—

Figure 1 is a side elevation of a grab, trolley and boom in operative position when the grab is being hoisted. Fig. 2 is an end elevation of the grab. Fig. 3 is a plan of the cushioning mechanism. Fig. 4 is a vertical section of the cushion, showing its attachment to the trolley. Fig. 5 is a section taken on line 5—5 of Fig. 2, the grab being open. Fig. 6 is a vertical section of one of the housings taken on line 6—6 of Fig. 7, and Fig. 7 is a section of the housing taken in a plane at right angles to the plane of Fig. 6.

A is the boom which is supported from a tower or other support in the usual way. Upon this boom runs the trolley B carrying the usual sheaves b, b¹ over one of which runs the hoisting rope c and over the other of which runs the operating rope d, these two ropes hoisting and operating the grab. One end of each of these ropes is attached to the trolley as at c¹, d¹. The trolley is provided with the usual wheels b² which run on the boom A.

F is a yielding stop or cushion shown as depending from the trolley B and adapted to be engaged by some portion of the grab mechanism as it rises, such for example, as the sheave housing C. The details of these parts are shown in Figs. 3 and 4. The structure is

a dash-pot comprising a cylinder f having a support and guide-pin f¹ attached to its bottom and passing up through it and the lower portion of the plunger f², its upper end being held in the plunger by means of the washer f³ and nut. The plunger f² fits easily within the cylinder and as the grab E is pulled up towards the under side of the trolley, the sheave-housing C striking the under surface of this cylinder f, closes it against the plunger, thus forming an air cushion which relieves the impact or jar which would otherwise be caused by the engagement between the grab and the trolley. When the grab is lowered again the air leaks by the plunger and the cylinder falls off from the plunger by its own weight into the position shown in Fig. 4, or a spring may be used to start it if best.

The grab comprises two jaws E, E¹, which are hung by two pairs of arms e, e¹, from a pin C¹ having a nut on each end and which forms the axis of the hoisting sheave C². The jaws are also provided with pairs of arms e², e³, each of which carries a hub e⁴ through which passes a shaft or pin e⁵ having a nut on each end by which the shaft is kept in place within the hubs of these arms. Upon this same pin is an idler sheave G and its housing G¹. The upper ends of the arms e² carry a pin on which runs the operating sheave D¹ and the upper ends of the arms e³ carry a pin on which runs the operating sheave D. Each sheave is provided with its housing. The operating rope d runs from the trolley at d¹ as above described down around under the sheave D¹ and the sheave D and up again over the sheave b¹ on the trolley to the hoisting engine, bearing perhaps on top of the idler sheave G. This whole construction is such that under ordinary conditions, as shown in Fig. 1, the grab is hoisted by means of the rope c which passes under the sheave C², and the jaws of the grab are kept closed by means of the constant tension upon the operating rope d which holds the sheaves D, D¹ together as shown in Fig. 1. When, however, the operating rope d is released the grab opens owing to the weight which it carries and the sheaves D, D¹ and their supporting arms e², e³ all fall down around the shaft e⁵ so that the parts take the position shown in Fig. 5.

When this operation takes place it will be noted that considerable slack must be given to the operating rope d and this slack as it

lies between the sheaves D, D¹ bears upon the middle sheave G which up to this time has been a pure idler.

An important feature of my invention is the providing of suitable housings for these various sheaves so that the operating rope, for example, will always be maintained in the groove in the sheave and without wear upon the edge of the housing. These housings will be understood by reference more particularly to Figs. 2, 5, 6 and 7. I will first describe the housing for the sheave G. This housing comprises two parts G¹, G², similar in all respects and weighted upon that portion which hangs upon and below the shaft e⁵ in order that the housing may uniformly remain in this position. The housing is open at its periphery through approximately 270° of its circumference in order to furnish free access to the groove for the operating rope d, its lower portion being closed in to assist in weighting it.

The housings for the sheaves D, D¹ are similar in general character to that just described in that they are weighted so that they may always maintain a fixed relation to the horizontal irrespective of their position on the axis of the sheaves D, D¹, respectively, with relation to the arms e², e³. As will be noted from Figs. 6 and 7, the housing in this case comprises two disks d² bolted together through segments of a rim d³, d⁴. The portions d⁵, d⁶ which are left open between the segments form passages for the rope d to reeve through as the relations of the sheaves change with relation to the idler G. d⁷ is a weight which is attached to the lower portion of the housing of each of these sheaves D, D¹ to keep the housing always in proper relation to the other parts as above described so that the operating rope d where it passes into and out of the housing will always do so without engagement with any portion of the housing, whether the parts are in the position shown in Fig. 1 or in Fig. 5. To insure the proper weighting of the housing in addition I prefer to provide openings such as d⁸ to reduce the weight of the upper portion of the apparatus.

The housing C¹ is similar in character to the other housings, sufficient openings between the two portions being allowed for the rope c to adjust itself as circumstances may require. Idlers C², C³ pivoted between the pairs of arms e, e and e¹, e¹, hold the rope when slackened from falling out of the groove in the sheave C².

It will be seen from this description when taken in connection with Figs. 5, 6 and 7, that the arms e², e³ by which the jaws are operated or allowed to operate, act like scissors. When the grab is to be opened the operating rope d will be released; the sheaves D, D¹ will fall one on each side of the shaft e⁵, being impelled thereto by the weight

which the grab holds and as they fall the parts will take the position shown in Fig. 5, their housings maintaining their relation with the horizontal, but the arms e², e³ taking a nearly parallel position, the operating rope resting upon the sheave G.

Other means for weighting the housings may be easily devised which will embody the invention above referred to, but the above described embodiment is simple because it enables the grab to be dismantled without undue trouble.

Variations in the construction of the cushioning device will also occur to anyone skilled in the art, the most obvious variation being the reversal of the parts, placing the yielding member upon the grab and the fixed member upon the trolley, and another variation, useful when the grab is always brought up not against a trolley but against a particular portion of the boom, is to locate one of the members upon the boom at that point.

What I claim as my invention is:

1. A hoisting apparatus of the character specified comprising a grab having swinging jaws, crossed arms secured to said jaws, a pivotal support at the intersection of said arms, sheaves carried by said arms beyond the point of intersection thereof, which sheaves are adapted to receive a rope by which said jaws may be operated, and a sheave mounted upon the pivotal support of said intersecting arms and coöperating with the sheaves carried thereby, substantially as described.

2. A hoisting apparatus of the character specified comprising a grab having swinging jaws, a pair of arms secured to each of said jaws and arranged whereby the pairs of arms may cross one another, a pivotal support for said crossed arms, a sheave carried by each pair of arms upon the outer ends thereof, said sheave being adapted to receive a rope by which said jaws may be operated, and a sheave mounted upon the pivotal support of said arms with which the sheaves carried by said arms are adapted to coöperate whereby the rope operating the jaws of the grab may be maintained in a proper operative position with respect to said sheaves.

3. A hoisting apparatus of the character specified comprising a grab having swinging jaws, crossed arms secured to said jaws, a pivotal support for said intersecting arms, an idler sheave mounted upon said pivotal support, sheaves carried by said arms and adapted to receive a rope for operating said jaws, said sheaves being located on said arms to be carried around said idler sheave and coöperate therewith during the operation of said arms; whereby the operating rope may be maintained in a constant operative position by said idler sheave, and means for over-weighting said sheaves to

maintain a proper upright position for said rope to render freely over the same.

4. In a coal hoisting apparatus, a grab having a hoisting means and operating means, said operating means comprising two pairs of crossed arms pivotally connected together, each of said pairs of arms being connected to one of the jaws of said grab at one end and carrying an operating sheave at its outer end, an idler sheave mounted on the pivot of said arms, said idler sheave so coöperating with said sheaves that an operating rope passing round said operating sheaves may lie approximately in contact with the upper periphery of said idler sheave when said rope is taut, and may rest upon a larger portion of the periphery thereof when said rope is loose, said sheaves being provided with weighted housings adapted to be maintained always in the same position with relation to the horizontal, as described.

5. In a coal hoisting apparatus, a grab having hoisting means comprising a hoisting sheave and hoisting rope surrounding said sheave, and operating means comprising one or more operating sheaves and an operating rope, each of said sheaves being provided with housings weighted to maintain them always in substantially the same vertical position.

6. In a grab mechanism, a sheave having a housing weighted to maintain it in a vertical position.

7. In a coal hoisting apparatus, a yielding stop for the grab comprising a chambered member and a plunger having a sliding fit therein whereby upon the impact of the grab air may be compressed within said chambered member and gradually expelled therefrom thereby providing a yielding stop to the grab.

8. In a coal hoisting apparatus, a yielding stop for the grab comprising a hollow plunger, a chambered member into which said plunger is adapted to fit and slide therein, a rod attached to said chambered member and extending through the end of said plunger, and means located and movable within said plunger for securing the end of said rod.

9. In a coal hoisting apparatus, a yielding stop having a plunger and cylinder fitted to said plunger, means for allowing the air to pass from the chamber within the cylinder to the atmosphere, means for guiding the movement of said cylinder with relation to said plunger, as set forth.

JEREMIAH CAMPBELL.
